UNITED STATES PATENT OFFICE.

JOHN JAMES KNIGHT, OF TORONTO, ONTARIO, CANADA.

DRAW-HEAD FOR RAILWAY-CARS.

SPECIFICATION forming part of Letters Patent No. 388,882, dated September 4, 1888.

Application filed June 2, 1888. Serial No. 275,892. (No model.)

To all whom it may concern:

Be it known that I, JOHN JAMES KNIGHT, carpenter, of the city of Toronto, in the county of York, in the Province of Ontario, Canada, 5 have invented new and useful Improvements in Draw-Heads for Railway-Cars; and I do hereby declare that the following is a full, clear, and exact description of the same.

My invention relates to draw-heads now in 10 use with the common link and pin; and it consists in a sliding trip operated backward by the link when being pushed into the draw-head, and forward by a spiral compression-spring. The trip consists of a round bar with flattened 15 end having a hinged head-piece thereon, which is pressed up on the under side of the roof of the draw-head by a common flat spring doubled in the middle, and is kept down by a small pin in the said roof behind the draw-pin, allowing 20 the spiral compressed spring to force the trip forward to hold the link or pin, as the case may be. The said spiral spring acts directly on the head-piece in front and on a stationary block behind, and is supported by the round 25 bar forming a part of the trip hereinbefore referred to.

Reference being had to the accompanying drawings, Figure 1 is a side view of my draw-head with one of the sides removed to show the 30 working parts thereof. Fig. 2 is a plan view with the upper part or roof removed for the same purpose. Fig. 3 is a detached side view of the head-piece, showing in dotted lines the flat spring hereinbefore referred to.

35 Similar letters of reference indicate similar or corresponding parts.

A represents the draw-head; *a*, the upper part or roof of the same; *b*, the under part or floor of the same; *c*, the left side thereof; *d*, the 40 right side; *e*, the hinged head-piece of the trip; *e'*, the pivot pin thereof; *e''*, a sloping notch; *f*, the flat end of the bar *g*, with flat spring *h* in dotted lines, hereinbefore referred to; *i*, the spiral compression-spring, which forces forward 45 the trip by acting on the head-piece *e* in front and the block *j* behind. *k* represents the pin

and *l* the link; *m*, the small pin in the roof for keeping down the head-piece *e*. A cross-pin, *n*, is also shown in a notch in the aforesaid pin *m*.

The operation of the trip when coupling is as follows: The coupling-link is of such length that in coupling the cars the draw-heads will come in contact before each head piece will have traveled two inches, or nearly so, so that the 50 force of the percussion from the cars coming together will be received by the percussion-spring on the inner ends of the draw-heads and will be spent therein, and protecting the trip from being damaged thereby.

Having thus described my invention, I claim—

1. A sliding trip for the draw-head of railway-cars, constructed with a head-piece hinged on the front and flat end of a round bar provided with a flat spring for pressing up the head-piece on the under part of the roof of the draw-head, and a spiral compression spring with fulcrum-block behind for pressing forward the trip, said head-piece kept down by a 65 small pin in the roof of the draw-head.

2. In a draw-head constructed with the common link and pin and percussion-spring at the back end thereof, the combination of a sliding trip with head-piece *e*, pivot-pin *e'*, and small 75 pin *m* on roof of the draw-head with notch and cross-pin *n*, a bar, *f g*, with flat spring *h*, spiral compression-spring *i*, with fulcrum-block *j*, arranged and operating as set forth.

3. The under part of the roof of the draw-head constructed with a notch, *e''*, sloping upwardly toward the mouth thereof to receive and hold in position the hinged head-piece *e* of the trip previous to the action of the link thereon.

JOHN JAMES KNIGHT.
